INFLATABLE ARTICLES
 Edmund C. Barbera, 55 Hillandale Road,
 Portchester, N.Y.
 Filed May 5, 1965, Ser. No. 453,437
 5 Claims. (Cl. 152—338)

This invention relates to inflatable articles, and more particularly concerns flexible walled, chambered articles in the form of inner tubes for automotive vehicles; life jackets, rafts; inflatable toys, and the like.

Various expedients have been proposed to cope with the puncture of inflated articles, particularly, the inner tubes of motor vehicles. Thus, it has been suggested that the tube be chambered, so that the puncture of a single chamber will leave the other chambers still in their inflated condition; and thus avoid danger accruing from the sudden puncture or blowout of the conventional inner tube.

However, the suggested multichamber constructions for inner tubes display one or more disadvantages, relating to complexity of the construction; partial effectiveness; excessive cost, or the like. Thus, the multichamber type of inner tube has not come into any substantial actual usage.

Accordingly, an object of this invention is to provide an improved inflatable article, of the multichamber type, useful as an inner tube, life raft, etc., which has a relatively simple construction making the same inexpensive to manufacture; which is readily manipulated in use and which is highly effective in markedly reducing dangers incident to puncture or blowout of an inner tube.

Another object of this invention is to provide in a multichamber, inflatable article, improved means for independently inflating and sealing each individual chamber of the article so as to maintain the inflated condition of the various chambers despite the puncture of any given chamber.

Still another object of this invention is to provide in articles of the character described, improved inflating means including dual air conduit means coactive to inflate and seal each chamber independently of the other chambers, yet being effective to retain the chamber sealing function for all chambers other than a chamber which has been punctured.

Other objects of this invention will in part be obvious and in part hereinafter pointed out.

In the drawings, FIG. 1 is a front elevational view showing an inflatable article, in the form of an inner tube, embodying the invention, with parts cut away and parts in section;

FIG. 2 is a transverse sectional view taken on the line 2—2 of FIG. 1;

FIG. 3 is an enlarged longitudinal sectional view showing the interconnected segments of the article;

FIG. 4 is an enlarged sectional view showing the terminal ends of the inflating and sealing means thereof;

FIG. 5 is a partial front elevational view, with parts cut away and parts in section; showing an alternative embodiment of the invention.

Essentially, the instant invention comprises an inflatable article such as an inner tube for automotive vehicles, or the like, which is formed with a plurality of individually sealed chambers in adjacent relation to each other, with outer configurations in accordance with the nature of the specific article. Inflating and sealing means is provided in the form of a pair of coaxially related, flexible tubings which pass through the several chambers; each tubing having a valved air inlet means. The outer of the coaxial tubings is perforated along the length thereof, whereas the inner tubing is imperforate. The tubings are so arranged at their coterminous ends that one of the valved inlet means is effective to admit air between the coaxial

2

tubings and thus inflate each of the chambers via the perforations in the outer tubing, while the other valved inlet means is effective to admit air into the inner tubing so as to inflate the same into sealing contact with the outer tube, thus closing off the perforations therein.

As shown in FIGS. 1—4, 10 designates an inflatable article embodying the invention, in the form of an inner tube for the tires of an automotive vehicle. The same is of the usual doughnut shape, being made up of a plurality of similar segments generally indicated at 11. Each segment 11 is in cylindrical form; the successive segments being in telescoped and integrated relation to each other about the circumferential extent of the article. A terminal segment 12, hereinafter described in detail, interconnects a pair of segments 11.

Each of the segments 11 is formed of a resilient material such as natural or synthetic rubber or other suitable elastomeric material. The segments 11 comprise a cylindrical wall portion 13 with a transversely extending end wall portion 14 at one end thereof and have an annular open end 15 at the other end thereof. The cylindrical wall portion 13 is tapered at the forward end thereof, as at 16, which tapered wall portion is telescopically received in the chamfered end portion 17 of the next succeeding segment 11, as shown in FIG. 3. It is understood that the telescoped portions 16, 17 of segments 11 are suitably cemented together to form the tube 10.

Means is provided for inflating and sealing the individual chambers 18 formed by the telescoped, successive segments 11. To this end, the end wall 14 of each segment 11 includes a flexible conduit portion 19 extending forwardly of said end wall 15; said conduit portion 19 being open at its forward end 20 and in communication with the chamber 18, at its rearwardly disposed end 21.

The conduit portions 19 are located adjacent the inner circumferential extent of tube 10, and somewhat remote from the outer circumferential extent thereof, as indicated in FIG. 1. Conduit portions 19 are of a length such that when segments 11 are integrated to form tube 10, the forward end 20 which is chamfered on its outer surface as at 22, is telescopically received in the rear end portion 21 which may be flared outwardly as at 23 to receive the same, of the adjacent segment 11. The thus telescoped conduit end portions 20, 21 are cemented together to thereby form a continuous conduit generally indicated at 23. Conduit 23 is perforated as at 24, along the length thereof, thus establishing communication between conduit 23 and each of the individual chambers 18.

In addition, a continuous length of flexible, inflatable tubing 25 is disposed within conduit 23 with the O.D. of tubing 25 substantially equal to the I.D. of conduit 23, so that the respective cylindrical walls thereof lie in contact with each other.

The coaxially related conduit 23 and tubing 25 have the opposite terminal ends thereof substantially coterminous as indicated in FIG. 4, being disposed in terminal segment 12. At one end of said coaxially related members, indicated at 26, the terminal end 27 of inner tubing 25 is sealed off against inner surface portions 28 of the terminal end 29 of outer conduit 23. This may be accomplished by the insertion of a tubular air inlet valve means 30 into terminal end 29 of conduit 23, with a sealing flange 31 secured to conduit end 29 and a wall surface portion of segment 12, through an opening 31A therein.

Thus, air under pressure may be admitted to conduit 23 by way of valved inlet means 30, and passing between tubing 25 and conduit 23 to perforations 24 along conduit 23 to inflate the individual chambers 18. The inner tubing 25 serves to seal off perforations 24 in conduit 23, and to this end, the other end of the coaxially related members 23, 25, indicated at 32, extend through an opening 33 therein. The coaxial terminal ends 34, 35

of conduit 23 and tubing 25 have their contacting wall portions clamped together throughout their circumferential extent by a second tubular air inlet valve means 36, and a sealing flange 37 secured to a wall surface portion of segment 12 at opening 33 therein, which brings air inlet valve means 30, 36 adjacent each other, FIG. 4.

Upon inflating chambers 18 to a selected pressure, by way of air inlet valve means 30; air under pressure is admitted by way of inlet valve means 36 to tubing 25 causing the same to inflate so as to seal off the perforations 24 in conduit 23, thus retaining the inflated pressure of each chamber 18. Preferably, the air pressure in inner tubing 25 is a few pounds greater than the air pressure in chambers 18.

In the event that any one of chambers 18 is punctured or blown out; the collapse of the punctured chamber will not materially effect the remaining inflated chamber 18. It has been found, that the inflated chambers 18 on either side of the collapsed chamber will tend to move circumferentially toward each other and thus reduce the gap therebetween. Since the circumferential extent of tube 10 may be subdivided into any given number of segments 11, the angular extent of each segment may be predetermined. It has been found that with a total of 18 segments 11, 12, giving each segment an angular extent of 20°, the size of chambers 18 are optimum for proper inflation and riding characteristics, as well as protection in the event of puncture or blowout of one of the chambers.

As shown in FIG. 5, the tube 10A, which is generally similar to tube 10, hereinbefore described, may be formed economically, using the lost wax process, to make the cylindrical wall 40 thereof integral with the transverse partition walls 41, forming the inflatable chambers 42. The partition walls 41 may be integrated, during the casting of the latex or rubber material forming cylindrical wall 40 and partition walls 41, with the outermost of the coaxially related flexible, resilient tubing 23A. Such tubing 23A is perforated at suitable intervals as at 24A to establish communication between tubing 23 and chambers 42.

The inner tubing 25A serves to seal the perforations 24A of tubing 23A, in the manner previously described; the terminal ends of tubings 23A, 25A, being brought out through openings in a terminal portion of cylindrical wall 40, and provided with respective air inlet valve means, all as hereinbefore described. Thus, tube 10A can be inflated as previously described in connection with tube 10, and puncture or blowout of any chamber 42 will not materially affect the remaining inflated chambers 42.

It will be apparent that conduits 23, 25; as well as tubing 23A, 25A, can be formed of rubber or other suitable elastomeric material, so that the same can be inflated to the extent necessary to effect the sealing operations as described above.

As various changes might be made in the embodiments of the herein disclosed invention without departing from the spirit thereof, it is understood that all matter herein shown or described, shall be deemed illustrative and not by way of limitation, except as set forth in the appended claims.

What is claimed is:

1. An inflatable article comprising a plurality of flexible, walled chambers in adjacent relation to each other, means for independently inflating each chamber comprising first flexible conduit means passing through opposed wall portions of each chamber and sealed thereto and second flexible conduit means disposed within said first conduit means, said first conduit means being formed with longitudinally spaced perforations to establish communication between said first conduit means and the interior of each of said chambers, valved air inlet means on said first conduit means for admitting air under pressure between said conduits for passage into each of said chambers

via the perforations in said first conduit means and valved air inlet means independent of said first mentioned valved air inlet means on said second conduit means for admitting air under pressure into said second conduit means for inflating said second conduit means into sealing contact with the inner surface of said first conduit means thereby sealing the perforations thereof and maintaining the inflated pressure of each of said chambers, whereby puncture of the wall of any of said chambers will leave the remaining chambers in an inflated condition.

5 2. An inflatable article comprising a plurality of flexible, resilient walled chambers disposed in laterally related adjacent relation to each other, means for independently inflating each of said chambers comprising first flexible conduit means extending longitudinally through each of said chambers, the wall of said conduit means being perforated to establish communication between said conduit means and the interior of each of said chambers, second flexible conduit means disposed within said first conduit means, the outer wall surface of said second conduit means being adjacent the inner wall surface of said first conduit means, first and second valved air inlet means independently mounted respectively on said conduits whereby air under pressure may be admitted selectively between the opposed wall surface portions of said conduits or into said second conduit to inflate the wall of said second conduit means into sealing relation to said first conduit means.

10 3. An inflatable article as in claim 2 wherein the coterminous ends of said conduits at one end thereof have the opposed wall portions at said one end thereof clamped together, and one of said valved air inlet means communicating only with the terminal end portion of the second conduit means, and the coterminous ends of said conduits at the other end are clamped together and the other of said valved air inlet means communicating only with the terminal end portion of said first conduit means.

15 4. An inflatable article as in claim 2 wherein each chamber comprises a tubular flexible, resilient walled member having a transversely disposed end wall at one end thereof and being open at the other end thereof, said end wall being formed with a conduit portion extending longitudinally forward thereof, said conduit portion being open to the forward end thereof and in communication with the interior of said tubular member at the rear end thereof, said tubular members being arranged in longitudinally related, telescoping relation with the rear open end of each tubular member in sealed engagement with the annular outer wall portion of the tubular member at the forward end thereof telescoped therein, and the forward open end of the conduit portion of one tubular member being telescoped and secured in the rear end of the conduit portion of the tubular member adjacent said one tubular member, said successive, telescopically engaged conduit portions of the adjacent tubular members forming said first conduit means.

20 5. An inflatable, walled article formed of flexible resilient material, said article comprising a plurality of sealed, air receiving chambers for inflating the same, means for inflating said article comprising a pair of coaxially related, flexible conduits extending through each of said chambers, the outer wall surface portion of the outer conduit being in sealed relation to chamber wall through which said outer conduit passes, said outer conduit being formed with longitudinally spaced perforations to establish communication between said outer conduit and the interior of each of said sealed chambers, said inner conduit being inflatable and imperforate; valved air inlet means arranged for connection to a terminal end of each of said conduits, means for engaging the coterminous ends of said conduits at one end thereof to clamp opposed wall portions thereof together throughout their circumferential extent, one of said valved air inlet means communicating with said inner conduit means at said one end thereof; and means for engaging the coterminous

ends of said conduits at the other end thereof to clamp and seal the other end of said inner conduit means, the other of said valved air inlet means communicating with the other end of said outer conduit means, whereby air under pressure may be admitted at said one valved air inlet means into said inner conduit means to inflate said inner conduit means into sealing contact with said outer conduit means, and air under pressure may be admitted at the other valved air inlet means into said outer conduit for independently inflating each of said

air receiving chambers, the puncture of any one sealed chamber leaving the other inflated chambers unaffected.
